UNITED STATES PATENT OFFICE.

HERMANN NEUMANN, OF BLACKWELL, WISCONSIN.

CAR-LOCKING DEVICE.

Application filed September 15, 1921. Serial No. 500,726.

To all whom it may concern:

Be it known that I, HERMANN NEUMANN, a citizen of the United States, residing at Blackwell, in the county of Forest and State 5 of Wisconsin, have invented certain new and useful Improvements in Car-Locking Devices; and I do declare the following to be a full, clear, and exact description of the invention, such as will enable others skilled 10 in the art to which it appertains to make and use the same.

This invention relates to an improved device which is especially, but not necessarily, designed for anchoring cars to the 15 rails on inclines so that in case the brakes fail to hold, there will be no chance of the car running away.

The principal object of the invention is to generally improve upon devices of this 20 class by providing one of extreme simplicity and durability which is merely composed of an arm which is attached to the car or other wheeled support, a pair of rail-engaging jaws which are carried by this arm, a hand- 25 operated locking lever and means for moving the jaws toward and from each other to render them effective or ineffective as desired.

Other objects and advantages of the 30 invention will be apparent during the course of the following description.

In the accompanying drawings forming a part of this specification and in which like numerals are employed to designate like 35 parts throughout the same:

Figure 1 is a side elevational view of a device constructed in accordance with this invention showing the same attached to a rail, portions of the arm and operating 40 handle being removed because of the lack of drawing space.

Figure 2 is a central vertical sectional view, with parts shown in elevation, taken substantially on the plane of the line 2—2 45 of Fig. 1.

In carrying out the invention I make use of a suitably shaped arm 1 which is designed to have its upper end connected in any suitable way with the car or other 50 desired body to be locked or anchored. This arm has its lower end directed laterally as indicated at 2 to permit it to bear on the head of the rail R. By referring to the 55 sectional view, it will be seen that the laterally directed portion 2 is formed at opposite points with sockets and coiled springs

3 are arranged in these sockets and serve a purpose to be hereinafter set forth. Adjacent these sockets, the portion 2 of the arm is formed with a transverse hole and a bolt 60 4 is passed through this hole and extends beyond the opposite sides of the arm. To prevent rotation of the bolt, a screw 5 is passed through the arm and engaged with the bolt as clearly shown in Fig. 2. Associated with this bolt 4 are a pair of rail engaging jaws 6 which have their lower ends bent inwardly toward each other as indicated at 7 to permit them to effectively engage the head of the rail. Each of the 70 jaws is provided near its opposite ends with relatively large inclined holes 8 and 9 respectively. By referring to these holes, it will be seen that they are sufficiently large to permit the jaws to have free or loose 75 movement on the bolt 4 which extends through them. It is to be noted that there are nuts 10 on the opposite ends of the bolt and these nuts serve to force the jaws toward one another to adjust them for proper 80 engagement with different sized rails and to form fulcrums for the jaws. As above pointed out, the jaws are formed near their upper ends with holes 9 and another bolt 11 is passed through these holes. This bolt 85 serves to connect the upper ends of the jaws together and to guide them when these ends are moved with respect to each other and serves the additional function of a fulcrum for the cam head 12 of the hand-operated 90 locking lever 14. It is to be noted that the cam-head 12 is so constructed as to permit the upper ends of the jaws to approach one another and in order to permit them to move very close together, they have their 95 inner faces inclined as indicated at 15 to permit them to engage the central portion of the cam head as indicated in dotted lines 100 in Fig. 2. In order to permit the jaws to take this position, the opposite sides of the aforesaid laterally directed portion 2 of the arm are bevelled as indicated at 16.

In use it will be seen that the jaws which were formerly held apart by means of the coiled spring 3 are fitted over the head of 105 the rail and the hand lever 14 is then gripped and moved from the dotted line position indicated in Fig. 1 to the full line position and in so moving it, it binds the laterally directed portion 2 of the arm against 110 the rail head and rocks the jaws into engagement with the rail. Assuming that the

upper end or other part of the arm 1 is chained or otherwise connected with the car, it will be seen that the latter will be anchored and prevented from moving along the track. By making use of this improved device, the car can be securely locked to the rails on steep inclines and even if the brakes fail to hold, the car will still be locked against movement as will be seen. Any tendency of the car to move on the track will tend to cant or tilt the jaws and cause them to obtain an even better grip than when truly vertical.

By carefully considering the description in connection with the drawings, persons familiar with devices of this class will doubtless be able to obtain a clear understanding of the invention. Therefore, a more lengthy and detailed description is deemed unnecessary.

Since probably the best results may be obtained with the construction and arrangement herein shown and described, this is taken as the preferred embodiment of the invention. However, I wish it to be understood that minor changes coming within the scope of the subjoined claims may be resorted to if desired.

I claim:

1. A car locking device comprising an arm adapted to be connected with a car, the lower end of said arm being turned laterally, a pair of vertically elongated jaws on opposite sides of said laterally turned arm

ends, the lower ends of said jaws being shaped to grip the ball of the rail, and a locking lever having a wedge-like cam pivotally mounted between the upper ends of said jaws, whereby to spread said upper ends and rock said jaws around their pivots to engage their lower ends with the rail.

2. A structure as specified in claim 1, said jaws and said laterally turned arm ends having relatively vertical movement, said wedge-like cam being provided with a peripheral surface adapted to engage said arm ends and force it into engagement with the rail when the locking lever is operated.

3. A car locking device comprising an arm adapted to be connected with a car, the lower end of said arm being turned laterally and bevelled at its opposite side toward its upper edge, a bolt passing through said arm end and extending beyond the bevelled side thereof, a pair of vertically elongated jaws, rockably mounted on said bolt at said bevelled sides, another bolt passing loosely through the upper ends of said jaws, and a locking lever having a wedge-like cam pivotally mounted on said last named bolt for inverting the upper ends of said jaws and rocking the latter upon said first named bolt, whereby to engage the lower end of said jaws with a rail.

In testimony whereof I have hereunto set my hand.

HERMANN NEUMANN.
